(57) **CLAIM**

The ornamental design for a carpenter's pencil, as shown and described.

DESCRIPTION

FIG. 1 is a front perspective view of a carpenter's pencil showing our new design;

FIG. 2 is a front elevational view of FIG. 1;

FIG. 3 is a rear elevational view of FIG. 1;

FIG. 4 is a top plan view of FIG. 1;

FIG. 5 is a bottom plan view of FIG. 1;

FIG. 6 is a left side elevational view of FIG. 1; and,

FIG. 7 is a right side elevational view of FIG. 1.

The broken line showing of environmental structure is for illustrative purposes only, and forms no part of the claimed design,
